UNITED STATES PATENT OFFICE.

HUGO SACK, OF DUSSELDORF, GERMANY.

DESIGN FOR A BAR OR COLUMN.

SPECIFICATION forming part of Design No. 34,036, dated February 5, 1901.

Application filed June 4, 1896. Serial No. 594,327. Term of patent 14 years.

To all whom it may concern:

Be it known that I, HUGO SACK, a citizen of the German Empire, residing at Dusseldorf, in Rhenish Prussia, Germany, have invented a new and original Design for a Bar or Column, of which the following is a specification, reference being had to the accompanying drawings, showing a part thereof.

Figure 1 is a perspective view of my design, and Fig. 2 is a transverse section thereof.

The bar or column designed by me comprises four plates *a*, radiating symmetrically

from a central axis *b*, so as to form four equal angles at said center, then bent into two parallel planes, as shown at *c*, and then into two planes at right angles thereto, as shown at *d*.

What I claim is—

The design for a bar or column, herein shown and described.

HUGO SACK.
